MAINE.

FEELER MECHANISM FOR LOOMS.

Application filed July 22, 1925. Serial No. 45,349.

This invention relates to such feeler mechanisms as are applied to automatic looms for causing the action of the automatic replenishing mechanism to function when the filling on the bobbin in the shuttle has become nearly exhausted.

In the form shown in a part of the accompanying drawings, the feeler is a right hand side swipe or slipping feeler. In 10 another part of the drawings, the feeler is shown reversed to make it left hand side swipe or slipping.

The object of the invention is to produce a feeler mechanism of simple and compact form, comprising a small number of parts and adapted to accurate and long continued performance without needing adjustment or repairing, whereby the feeler mechanism and the replenishing mechanism 15 may be adjusted for discharge of the bobbin from the shuttle with the smallest feasible quantity of yarn remaining on the bobbin as wastage, and whereby loss of time by stopping the loom is reduced.

20 A further object is to produce a feeler mechanism in a form to avoid accidents to the fingers and hands of operatives.

Reducing the quantity of yarn left on the bobbin when the transfer is made is a financially important matter. Under present 25 weaving practice, this wastage is relatively so large as to make, in the aggregate, a large loss item in the operation of a textile mill. In some lines of work this wastage is as 30 much as two per cent of the yarn. That means two tons of wastage out of one hundred tons of yarn. As wastage, this material is sold at a large loss per pound. Two tons of yarn are an important item.

35 By making the feeler action sensitive and accurate and durable, it is safe to so wind the bobbins as to provide for sliding of the feeler when the yarn on the bobbin is only sufficient to constitute a safe reserve length 40 of yarn until the bobbin has been discharged.

In the accompanying drawings,

Fig. 1 is a perspective view, with parts broken away, showing a feeler mechanism contained in the present invention and constructed for side slipping movement of the feeler to the right;

Fig. 2 is an upright section on the line,

2-2, of Fig. 1, looking in the direction of the arrow;

Fig. 3 is a plan of the supporting body, 55 the cover of said body having been removed to show the feeler and associated members, those parts being at rest with the feeler in its feeling position, perpendicular to the bobbin axis;

60 Fig. 4 is a view of the same mechanism with the feeler pushed endwise by a working supply of filling without sidewise movement;

Fig. 5 shows the same mechanism with 65 the feeler moved toward the right by contact with the nearly empty bobbin;

Fig. 6 is an upright section on the line, 6-6, of Fig. 3, looking toward the left;

Fig. 7 is an upright section on the line, 70 7-7, of Fig. 3, looking toward the left;

Fig. 8 is a transverse, upright section on the line, 8-8, of Figs. 2, 3 and 6, looking in the direction of the arrow;

Fig. 9 is an upright section on the line, 75 9-9, of Fig. 1, looking toward the right;

Fig. 10 is a detail perspective view of a key which controls the action of the cam follower hook;

Fig. 11 is a section on the line, 11-11, 80 of Fig. 9, looking toward the left, the key being connected for leftward movement of the feeler as shown in Fig. 12;

Fig. 12 is a view similar to Fig. 1, the feeler supporting body being reversed for 85 leftward movement of the feeler;

Fig. 13 is a detail section on a part of the line, 13-13, of Fig. 12.

These drawings show the body of the feeler mechanism only a little smaller than 90 the size of the mechanism in regular operation.

Referring to Figs. 1 to 11, inclusive, of the drawings, A is the base of the body of the feeler mechanism. Said body is horizontal and approximately rectangular as viewed in plan. A¹ is the cover for said body. A² is an upright bracket supporting said body. Said bracket has a flat horizontal head, A³, on which rests the base, A. A cap screw, A⁴, extends upward through said head into the base, A, to rigidly secure the base to the head. The bracket, A², is 100 suitably secured to a stationary part, A⁵,

of the loom by means of a bolt, A⁶, extending through a horizontal slot in the part, A⁵. An upright circumferential main wall, A⁷, rises from the bottom or floor of the base, A, and makes said base dish-form. But said wall is cut low at a part of the rearward end of the base to make an opening, A⁸, in which the feeler, B, may lie.

For convenience in description, it is assumed that the direction of the free end of the feeler is rearward.

In the rearward part of the base, a wall, A⁹, extends forward from about midway between the side walls, A⁷. The front part of said wall is tapped to receive the cap screw, A⁴. Rearward of said screw, said wall is tapped to receive the binding screw, A¹¹, which extends downward through the cover, A¹, to bind the cover firmly to the base, A. The cap screw, A⁴, is long enough to extend into the cover to its upper face, the cover having an opening larger than the diameter of the cap screw, in order that the cap screw will not engage the cover and in order that, when the body is inverted, as will be described further on, the cap screw will pass freely through the cover and into the base. The cover has a downwardly-directed circumferential wall, A¹³, which rests upon the wall, A⁷, of the base, A. The front part of the wall, A⁷, has a notch, A¹², and the cover wall, A¹³, has a downward extension or tooth, A¹⁴. Engagement of said tooth in said notch prevents the front part of the cover from moving sidewise on the base A.

About midway between the front and rear ends of the base, A, the left hand side wall is extended inward and forward to form a recess or bearing, A¹⁵, which normally receives the toe, B⁵, of the feeler, B.

The feeler, B, comprises the leg, B¹, the head, B², the foot, B³, the heel, B⁴, and the toe, B⁵. The leg is approximately parallel to the sides of the base, A. The foot is approximately parallel to the ends of the base, A. The heel, B⁴, normally bears against the right hand wall, A⁷, of the base, A, while the leg, B¹, bears against a face or stop, B⁶, on the wall, A⁷, at the left of the opening, A⁸. At the right of the toe, B⁵, the foot, B³, has a rearward curve, B⁷. Rearward of said curve the end wall, A⁷, is notched to leave a stud, C⁸, which receives the eye, C¹, of a contracting coiled spring, C. On the opposite end of said spring is a hook, C², which engages the foot, B³, in the curve, B⁷.

In the form shown in the drawings, the feeler is made of a piece of wire bent into the desired shape. The rib, A¹⁶, rises from the bottom of the body, A, beginning at the front wall, A⁷, and extending rearward parallel to the side wall and ending at the bearing, A¹⁵. A rib, A¹⁷, rises from the

body floor at the front wall and extends rearward through the opening, A⁸. Said ribs are of proper height to support the feeler at such height as will cause the feeler to almost touch corresponding downward-directed ribs in the cover, A¹. Thus the feeler is slid able in a horizontal plane lying between said ribs. And the feeler is not carried by other movable members. It is not on a fixed hinge. It is free or "floating".

The spring, C, normally tends to pull the feeler rearward. Such movement being limited by engagement of the toe, B⁵, in the stop or bearing, A¹⁵, and by contact of the feeler leg with the face, B⁶, said face forming an abutment or stop for the feeler leg.

Direct forward bobbin pressure on the feeler head, B², by yarn engagement which prevents sidewise sliding, causes the feeler to move forward bodily on a line perpendicular to the bobbin axis, the leg of the feeler sliding on the face, B⁶, and the heel of the feeler sliding on the right hand wall, A⁷, and the toe, B⁵, moving forward out of and away from the bearing, A¹⁵, and along the adjacent side wall. Engagement of the feeler head by yarn on the bobbin prevents such sidewise sliding.

But when the bare or substantially bare part of the bobbin presses forward against the head, B², the head slides toward the right on the bare part of the bobbin, the entire feeler turning on the toe, B⁵, the inner face of the bearing or stop, A¹⁵, serving as a fulcrum, the spring, C, being stretched through a distance which is short relative to the distance through which the head, B², of the feeler moves. In other words, during such movement the part of the feeler between the hook, C², of the spring and the end of the toe is a short arm of a lever, while the entire length of the feeler is the long arm of the lever. This relatively short stretching of the spring offers relatively small resistance to the sidewise sliding of the head of the feeler. Thus the mechanism is made more sensitive for action when the bare bobbin presses the feeler head. Thus more of the force exerted by the bobbin on the feeler head is conserved for transmission through the feeler to the transmission rod which is shifted for permitting actuation of the replenishing mechanism, as will be described further on.

The rightward sliding of the feeler continues until the leg, B¹, of the feeler bears against the face, A¹⁰, at the right of the opening, A⁸, said face constituting an abutment for limiting the rightward movement of the leg. When the bobbin again moves away from the feeler, the spring, C, causes reverse turning of the entire feeler on the

toe, B⁵, into the inactive or normal position, the feeler leg, B¹, again resting against the abutment or stop, B⁶, and the heel, B⁴, of the feeler again resting against the right hand base wall, A⁷.

The rightward movement of the feeler causes the rightward movement of the transmission rod, E, endwise. Said rod rests in a channel, E¹, formed in a lateral extension, A²⁰, of the base, A, of the feeler body, said channel allowing free endwise sliding of said rod. The left hand end of said rod bears against the feeler leg when the latter bears against the abutment, B⁶, so that when the feeler head begins rightward movement, the rod, E, is moved rightward in unison with the movement of the feeler leg.

F is an approximately horizontal actuator of well-known form and suitably supported for endwise movement and operatively connected with a bobbin transfer mechanism (not shown). On the rear end of the actuator is a head, F¹, which has a channel, F², parallel to the length of the actuator and opening downward. On the left hand side of said head are two upright walls, F³, parallel to each other and perpendicular to the length of the actuator. In the plane of the space between said walls, F³, the main wall of the actuator has a slot, F⁴, extending upward from the lower edge of the actuator. For endwise movement, the actuator is dependent upon action by the cam follower, G, which is positioned and actuated periodically by any well-known means (not shown) to move forward into the channel, F², of the actuator. But the cam follower makes no engagement with the actuator unless the body, F⁶, of the key, F⁵, extends across the channel, F², of the actuator high enough to be in the path of the shoulder, G², of the cam follower head, G¹. The key, F⁵, is placed between the walls, F³, the body, F⁶, of the key extending across the channel, F², and into the slot, F⁴. The head, F⁷, of the key is pivoted to the walls, F³, by means of a horizontal cotter pin, F⁸. The head, F⁷, extends above and below the pivot. In the upper part of the head is a bearing, F⁹, parallel to said pivot. In the lower part of the head is a bearing, F¹⁰, parallel to said pivot.

In Fig. 1, the transmission rod, E has its right hand end bent laterally and seated in the lower bearing, F¹⁰. The body, F⁶, of the key is so long and so heavy that it will normally turn downward and move the bearing, F¹⁰, and the transmission rod, E, toward the left, whereby the left hand end of the transmission rod is made to bear against the leg of the feeler.

When the rightward movement of the feeler leg forces the rod, E, toward the

right, that causes the lower part of the head, F⁷, of the key to turn toward the right, whereby the key is tilted to bring its body upward into the path of the shoulder, G², of the hook, G¹, of the cam follower, G. Then the next forward movement of the cam follower will engage the key body and through said body transmit forward motion to the actuator. This involves forward movement of the right hand end of the rod, E. The channel, E¹, may be sufficiently wide to permit the rod to make such slight lateral turning in said channel as will permit the forward movement of the right hand part of the rod. But it may be preferred to make said channel narrow and allow the rod to be sprung sidewise to the limited extent needed for the forward movement of the right hand end of the rod.

The transmission rod, E, is provided with one or more folds or bends, E². For making a close adjustment of the length of said rod, either of said folds may be expanded or compressed by the aid of any suitable tool. For making such extension, the blade of an ordinary screw driver may be placed into one of the folds and slightly twisted. For making such compression, a pair of pliers may be made to embrace one of the folds and the jaws of the pliers then pressed slightly toward each other.

When the feeler mechanism is to be used for left hand movement of the feeler on the bobbin, the cap screw, A⁴, is released and the feeler body placed up-side-down on the head, A³, of the bracket, A², the cover, A¹, of the body then resting on said head. Then the cap screw is extended upward through the opening in the cover and into the threaded part of the base, A. Thus the body is again firmly secured on the head, A³. Now the movement of the feeler from its rest position must be toward the left. The relation of the transmission rod, E, to the associated parts is now changed as follows: The right hand end of said rod is engaged in the upper bearing, F⁹, of the key head, in order that leftward movement of the rod will so tilt the key as to bring the key body into the upper or working position. (See Figs. 11 and 12). The left hand end of the rod, E, is extended across the upper face of the body and bent downward and then rightward to lie in the channel, E¹, against the feeler leg. (See Figs. 12 and 13). When the nearly empty bobbin presses against the feeler head and causes slipping of the feeler head, that slipping is toward the left, and that causes the feeler leg to push the rod, E, in the same direction, whereby, as above described, the key, F⁵, is tilted to bring the key body, F⁶, into its upper position, the position which causes engagement with the hook of the cam follower, G.

Now it will be seen that without change of structure, excepting the change in the transmission rod, the mechanism can be used for either rightward or leftward sliding of the feeler head.

When the feeler supporting body is in either the position for right hand slipping or left hand slipping, said body may be adjusted sidewise, by means of the bolt. 10 A⁶, to bring the feeler head into the desired position relative to the bobbin. This feature is useful because inverting said body for left hand slipping places the feeler head farther toward the left.

15 In the cover, A¹, is a port, O, for the introduction of lubricating oil. In the base, A, is a similar port, O¹, for the same purpose. In the bottom of the base, A, near the opening, A⁸, is a recess, O², to hold lubricating oil.

20 Attention is again directed to the simplicity of the feeler supporting body, the feeler, and the spring, and the small size of the feeler supporting body. The small size of said body reduces cost and makes convenient handling; but a still further and important advantage in this connection is the fact that on many looms now in use there is room for applying this small structure where there is not room for a larger structure, the placing of the larger structure requiring expensive alterations in that part of the loom.

Locating the spring, C, as in our construction contributes materially to attaining the small size of the feeler supporting body. The spring is at the side of the feeler foot toward the head, B², of the feeler. Thus the space in the body at the opposite side 25 of the foot need be only large enough to allow the movement of the foot in that direction as far as is needed when the filled bobbin strikes the feeler head or to make room for the heel, B⁴, when the feeler head 30 slides on the empty bobbin. The spring, C, is a contracting or pulling spring. If it were located at the other side of the foot, B³, it would be an expanding or pushing spring and would need to have associated 35 with it other parts which would require more space than the length of the spring. Hence the feeler supporting body would require at that side of the feeler foot as much 40 space as the length of the spring when expanded plus the length added for the members which support and guide the spring 45 when it acts by expanding or pushing.

Furthermore, when the pulling spring is 50 used, more delicate action of the feeler is attained. The spring may be weaker and more easily overcome to permit movement of the feeler. The pulled spring may be entirely free excepting at its ends. One end 55 engages the tooth or lug, C³, and the other end engages the foot at B⁷. Between those

engaging points, the spring is suspended, not in contact with any member whereby frictional engagement is made. In other words, frictional resistance is avoided excepting that there may be slight frictional movement on the part, B⁷, of the foot or on the lug, C³. Hence this may be termed a floating spring. When the pushing spring is used, a stem must extend through the spring to make more or less contact with the coils of the spring, and that stem is usually pivoted and sliding at its base end, while at the other end a yoke or collar is fixed on the stem to form an abutment for the adjacent end of the spring, that yoke or collar being slidable on adjacent fixed parts of the structure, and the stem itself between that abutment and the head of the feeler being slidable in fixed members, whereby friction is made. Thus when the filled bobbin strikes the head, sufficient pressure must be exerted by the bobbin on the head to overcome all these elements of friction and also the inertia resulting from the greater mass of material in the spring and parts associated therewith. When an empty part of the bobbin strikes the head, similar large force must be exerted to shift the feeler by causing a partial endwise movement. In one form of feeler mechanism largely used, sidewise movement of the head of the feeler involves sliding of an arm of the stem on a cam to compel endwise movement of the stem during sidewise movement. Movement of this arm over the cam. 100 causes additional friction. During the return of the stem to normal position, after slipping, there is again movement on this cam, and the spring must exert a force sufficient to overcome the several factors of friction, and in so doing, the spring is at a disadvantage on account of the position in which it exerts its force, such friction being transverse to the cam face.

105 In our construction, the feeler is so supported as to produce the smallest amount of friction during its movements. As already herein stated, the feeler is free or "floating." It is also very light, so that 110 inertia is brought to a minimum. We have made it of wire of substantially the thickness shown by Figs. 3, 4 and 5, of the drawings. It has also already been pointed out that the spring is so associated with the foot of the feeler as to require a movement of the spring through a shorter range than the range of movement of the head during 115 sidewise slipping on the empty bobbin. This reduces strain on the spring.

120 Attention is also asked to the fact that the head, A⁸, of the standard, A², is turned toward the bobbin path whereby the feeler supporting body is brought closer to the bobbin. At the same time the bearing, A¹⁵, 125 for the toe, B⁵, of the feeler is placed well

toward the bobbin, whereby the distance between said bearing and the feeler head is made comparatively short, whereby the line of force acting through the feeler head and said bearing is much inclined, as will be seen by noting the lines, *a* and *b*, on Fig. 3. This inclination makes slipping of the head on the empty bobbin easier than would be the case if the slanting line, *a*, were more

10 nearly parallel to the line, *b*.

By making the feeler free and "floating" and associating with it a delicate spring, the endwise parallel movement of the feeler when the feeler head is engaged by bobbin 15 yarn, that movement is effected with less resistance by the head to the bobbin yarn, or with a lighter impact between the feeler head and the bobbin yarn. The lighter this impact is made, the less will the yarn be battered or bruised by the feeler head. Thus 20 our feeler mechanism is adapted to be used on looms in which the bobbin yarn is delicate.

It is also to be observed that the engagement 25 between the feeler and the adjacent end of the transmission rod, *E*, is made in a manner calculated to afford a minimum amount of friction. No intermediate sliding member making friction is used.

30 It is also to be observed that all the parts of this mechanism are adapted to economical manufacture and to easy assembling and adjustment and separation and to easy reversal to change the direction of the sliding 35 of the feeler.

It is also to be noted that the base, *A*, and the cover, *A'*, enclose the feeler, *B*, and the spring, *C*. Thus these parts and the lubricant within the body are kept free from dirt 40 and lint. This keeps these parts in condition for easy and quick movement, a condition necessary for prolonged and accurate and reliable service.

Furthermore, this construction has an important bearing upon safety for operatives. 45 In forms of feeler mechanisms now in use on looms, the working parts are so exposed as to often cause the pinching of the hands or fingers of the operatives, the mechanisms being so located as to permit accidental bringing of the hand or fingers into engagement while the attention of the operative is directed elsewhere. Hands of operatives injured in this way frequently require treatment. 50 In our improved mechanism the base, *A*, and the cover, *A'*, render the mechanism safe in this respect. The hand of the operative may rest on this part of the mechanism without injury.

60 And finally attention is again invited to the fact that the moving parts of the feeler mechanism consist of only two parts, a light feeler and a light spring—a "floating" feeler and a "floating" pull spring, these 65 two members being so positioned as to allow

making the body of the mechanism small and the action delicate.

We claim as our invention:

1. In a feeler mechanism for looms, the combination of a feeler stand, a floating 70 side slipping feeler non-pivotedly mounted directly on the feeler stand and movable thereon towards and from the front of the loom and in a direction longitudinally of the shuttle, an arm projecting laterally 75 from the feeler, a stop or bearing adapted to be engaged by said arm when the feeler is in rearward position, and a spring acting rearwardly upon the floating feeler and tending to move the feeler on the feeler 80 stand to its rearward feeling position.

2. In a feeler mechanism for looms, the combination of a feeler stand, a floating non-pivotedly mounted side slipping feeler 85 movable bodily directly on the feeler stand, a projecting arm extending laterally from the feeler, a stop or bearing located at one side of the floating feeler and adapted to be engaged by said arm when the feeler is in rearward position, and a pull spring acting 90 upon the said arm to move the floating feeler on the feeler stand to its rearward feeling position.

3. In a feeler mechanism for looms, the combination of a feeler stand, a floating 95 non-pivoted side slipping feeler mounted to slide directly on the feeler stand and having a laterally projecting arm, a stop or bearing positioned to be engaged by the laterally projecting arm when the feeler is 100 in rearward feeling position and constituting the fulcrum of the feeler during its side slipping movement, a spring acting in a rearward direction upon the laterally projecting arm to move the feeler rearwardly 105 and opposing its side slipping movement when the feeler side slips about the stop or bearing as a fulcrum.

4. In a feeler mechanism for looms, the combination of a feeler stand or support, a 110 floating side slipping feeler which is mounted to slide directly on the feeler stand or support, and having a laterally projecting arm, a fixed stop or bearing adapted to be engaged by the laterally projecting arm 115 when the floating feeler is in its rearward position, and a pull spring acting to move the feeler to its rearward position and to oppose side slipping movement of the feeler when the filling is substantially exhausted 120 on a detecting beat and the feeler tends to side slip about the stop or bearing as a fulcrum.

5. In a feeler mechanism for looms, the combination of a non-pivoted side slipping 125 feeler having a rigidly connected lateral projection, a stop or bearing positioned to be engaged by the lateral projection and constituting the fulcrum of the feeler during its side slipping movement, a spring con- 130

nected to the lateral projection between the stop or bearing and the feeler and acting in a rearward direction upon the feeler, and a second stop adapted to be engaged by the feeler for determining its direction when in feeling position.

6. In a feeler mechanism for looms, the combination of a non-pivoted side slipping feeler having a laterally projecting arm, a stop or bearing adapted to be engaged by the laterally projecting arm and constituting the fulcrum of the feeler during its side slipping movement, a second stop adapted to be engaged by the feeler, and a spring connected to the laterally projecting arm between the two stops and normally acting to move the feeler into its rearward feeling position with the arm and the feeler engaged with their respective stop which thus determine the feeling position of the feeler.

7. In a feeler mechanism for looms, the combination of a feeler stand having trackways constituting supports, a side slipping feeler having a laterally projecting arm and slidably supported by the trackways, a stop or bearing on the feeler stand adapted to be engaged by the laterally projecting arm and constituting a fulcrum for the feeler during its side slipping movement, and a spring acting upon said arm between the stop or bearing and the feeler and normally tending to move the feeler to rearward feeling position.

8. In a feeler mechanism for looms, the combination of a feeler stand and cover having trackways, a side slipping feeler having a laterally extending arm and mounted for sliding and side slipping movement between the trackways, a stop or bearing adapted to be engaged by the laterally extended arm, and a spring connected to the laterally extended arm at a point between the stop or bearing and the feeler and normally acting to move the feeler bodily between the trackways to its feeling position.

9. In a feeler mechanism for looms, the combination of a feeler stand or support, a floating side slipping feeler mounted for bodily movement towards and from the front of the loom and longitudinally of the shuttle directly on the feeler stand or support, an arm extending laterally from the floating feeler, a stop or bearing adapted to be engaged by said arm when the feeler is in rearward feeling position, and a spring acting upon the feeler to move it to rearward feeling position.

10. In a feeler mechanism for looms, the combination of a feeler stand and cover having trackways, a feeler having a lateral projection and confined between the trackways for bodily and side slipping movements, a stop or bearing adapted to be engaged by the lateral projection, a second stop adapted to be engaged by the feeler when it is in feel-

ing position, and a spring acting upon the lateral projection between the stop or bearing and the feeler to hold the feeler and projection against their respective stops and the feeler in feeling position.

11. In a feeler mechanism for looms, the combination of a feeler having a rearwardly extending leg, a heel portion at one side of its longitudinal axis and a projecting arm extending laterally to the opposite side of its longitudinal axis, a spring connected to the laterally projecting arm between the end thereof and the longitudinal axis of the feeler to move the feeler rearwardly, a stop or bearing adapted to be engaged by said arm under the influence of the said spring, and a feeler stand having feeler guiding portions between which the heel and arm of the feeler are guided as it is moved towards and from the front of the loom.

12. In a feeler mechanism for looms, the combination of a feeler stand having laterally separated feeler guiding portions, a side slipping feeler having a laterally extending heel for guidance by one of said guiding portions and an arm extending laterally from the feeler to the opposite side thereof for guidance by the other of said guiding portions, a stop or bearing at one side of the feeler adapted to be engaged by said arm, and a spring acting to move the feeler to its rearward feeling position between the guiding portions.

13. In a feeler mechanism for looms, the combination of a feeler stand having laterally separated guiding portions, a side slipping feeler bodily movable on the feeler stand between said guiding portions and having a heel offset laterally to one side of the feeler and an arm extending laterally to the opposite side of the feeler for engagement by the guiding portion of the feeler stand as the feeler is moved bodily towards and from the front of the loom, and a spring connected to the feeler between the adjacent guiding portion of the feeler stand and normally acting to move the feeler rearwardly between the guiding portions of the feeler stand.

14. In a feeler mechanism for looms, the combination of a feeler stand having laterally separated guiding portions and an opening at its rear between the guiding portions through which a feeler may extend and have lateral movement, a side slipping feeler bodily movable on the feeler stand between said guiding portions and having a heel offset laterally to one side of the feeler and an arm extending laterally to the opposite side of the feeler for engagement by the guiding portions of the feeler stand as the feeler is moved bodily towards and from the front of the loom, and a spring connected to the said arm between the adjacent guiding portion of the feeler stand and

feeler and normally acting to move the feeler rearwardly between the guiding portions of the feeler stand.

15. In a feeler mechanism for looms, the combination of a feeler stand having laterally separated feeler guiding portions and a laterally extending opening at its rear between said guiding portions, a side slipping feeler extending through said opening and having a heel offset laterally to one side of the longitudinal axis of the feeler to engage the adjacent guiding portion of the feeler stand and position the feeler laterally at one side of the guiding portion with capacity for side slipping movement towards said guiding portion, an arm extending laterally from the other side of the longitudinal axis of the feeler, a stop or bearing at the same side of the feeler adapted to be engaged by said arm, and a spring connected to the arm between the stop and feeler and normally acting to move the feeler to feeling position.

16. In a feeler mechanism for looms, the combination of a feeler stand, a side slipping feeler mounted for bodily movement on the feeler stand and having a laterally extending arm, a stop or bearing at one side of the feeler for engagement by said arm, a second stop for engagement by the feeler, and a spring acting upon the arm between the stop or bearing and the feeler for moving the feeler on the stand into its feeling position with the arm engaged with the stop or bearing and the feeler engaged with the second stop to position the feeler.

17. In a feeler mechanism for looms, the combination of a feeler stand, a side slipping feeler mounted on the feeler stand and having a laterally extending arm at its front portion resting on the feeler stand, a stop or bearing adapted to be engaged by the arm at one side of the feeler, a second stop adapted to be engaged by the feeler, and a spring connected to the arm between the stop or bearing and the feeler and acting to cause engagement of the stop or bearing by the arm and the engagement of the second stop by the feeler with the feeler in feeling position.

18. In a feeler mechanism for looms, the combination of the feeler stand, a non-

pivotal side slipping feeler mounted for bodily floating movement on the stand and displaced laterally by the forward pressure of a surface within the shuttle when the filling is substantially exhausted on a detecting beat, a heel extending laterally from one side of the feeler, an arm extending laterally from the other side of the feeler, a stop or bearing located rearward of and adapted to be engaged by the arm, and a spring connected to the arm between the stop or bearing and the feeler and acting through the arm to impart a rearward impulse to the feeler.

19. In a feeler mechanism for looms, the combination of a feeler stand, a non-pivotal feeler mounted on the stand for movement towards and from the front of the loom and in a direction longitudinally of the shuttle and having a laterally extending arm, guides for directing the movements of the feeler on the stand, a stop or bearing at one side of the longitudinal axis of the feeler, a spring connected to the arm between the end thereof that engages the stop or bearing and the longitudinal axis of the feeler and tending to maintain the feeler in rearward feeling position.

20. In a feeler mechanism for looms, the combination of a feeler support comprising complementary base and cover portions, means for securing the feeler support in position with either side uppermost, a feeler mounted between the base and cover, an actuator, a transmitter between the feeler support and actuator, a pivotally mounted key having an extended body portion operatively positioned by pivotal movement of the key in one direction, a head on the pivotally mounted key provided with two bearings, one above and the other below the pivot of the key for selective connection with the transmitter to cause pivotal movement of the key in the same direction and thereby operatively position the body portion of the key when the feeler support is reversed.

In testimony whereof we have signed our names, this 20th day of July, in the year one thousand nine hundred and twenty-five.

LARKIN H. BROWN.
GEORGE E. REPASS.
